UNITED STATES PATENT OFFICE

1,973,451

BLAST FURNACE CHARGING HOPPER

William S. Unger, Munhall, Pa.

Application December 27, 1932, Serial No. 649,082

2 Claims. (Cl. 219—19)

This invention relates to improvements in blast furnace charging hoppers, and has for one of its objects the provision of a novel construction enabling the hopper to be quickly and evenly heated, and thus obviate the usual freezing of materials at this point in extremely cold weather.

Another object is to provide a structure which will be cheap and easy to install, readily accessible, and one which will require but little attention and expenditure to maintain.

These and further objects of the invention will be apparent after referring to the drawing, in which:

Figure 1 is a sectional elevation of the apparatus of the invention.

Figure 2 is a diagrammatic plan of the invention.

Figure 3 is a sectional view taken on the line III—III of Figure 1.

Referring more particularly to the drawing, the numeral 2 indicates the charging stack of a conventional blast furnace. The stack 2 is provided with a metallic charging hopper 3 having a number of outwardly extending integral ribs 3^a on its outer surface. The outwardly extending integral ribs 3^a form a plurality of compartments, in each of which there is disposed a conventional electric space heater 4. The heaters 4 comprise a series of resistance strips 4^a which are connected together in parallel by means of the terminals 4^b. Suitable insulation is provided for each of the strips 4^a.

Each compartment is provided with heat and electrical insulation 5, such as asbestos. A removable plate 6, having handles 6^a, covers all of the elements in each of the compartments.

Electric current is supplied to the heaters 4

by a suitable wiring system, but as such forms no part of the invention.

A switch A, for initiating the operation of the heaters, is located in the customary stock house adjacent the bottom of the blast furnace.

A magnetic switch, or contactor, B is arranged in proximity to the heaters 4 and in parallel with the circuit thereto. The contactor B is energized by the switch A in the stock house through a separate circuit. A safety light C is arranged in series with the circuit to the heaters 4 and located adjacent the switch A for indicating their operation.

A manually operated switch D is located near the heaters to open the circuit from that position if such a necessity arises.

While I have shown and described one specific embodiment of my invention it will be understood that I do not wish to be limited exactly thereto, since various modifications may be made without departing from the scope of my invention, as defined in the following claims.

I claim:

1. In a blast furnace, the combination of a charging hopper, compartments being defined by integral ribs on the outer side of said hopper, electrical heating elements disposed in said compartments, and removable means for covering said compartments.

2. In combination with a material handling hopper, compartments being defined by integral ribs on the outer sides of said hopper, electrical heating elements disposed in said compartments, heat insulating media for said heating elements, and removable means for covering said compartments.

WILLIAM S. UNGER.
